UNITED STATES PATENT OFFICE.

JOSEPH D. MURVINE, OF AKRON, OHIO.

STAIR-GAGE.

1,261,596.

Specification of Letters Patent.

Patented Apr. 2, 1918.

Application filed May 1, 1917. Serial No. 165,731.

To all whom it may concern:

Be it known that I, JOSEPH D. MURVINE, a citizen of the United States, residing at Akron, in the county of Summit and State 5 of Ohio, have invented certain useful Improvements in Stair-Gages, of which the following in a specification, reference being had therein to the accompanying drawing.

The present invention relates broadly to 10 improvements in measuring instruments and more particularly has reference to a stair gage.

The invention as its principal object, contemplates the provision of an improved 15 gage of the character described embodying a pair of adjustably connected adjustable members through the medium of which a mechanic or carpenter may by placing the device on the stringers of the stairway and 20 adjusting the members against the skirting boards obtain the length and cut of both the tread and riser portions of the stairway in one operation, thus providing an improved labor-saving device.

More particularly, the present invention 25 embraces the provision of novel means for adjustably connecting a pair of adjustable members which constitute tri-squares.

More specific objects of the present invention consist in the provision of novel means 30 for preventing relative transverse movement of the adjustable members subsequent to adjusting them relative to each other; and to provide novel means for adjustably 35 connecting the blades or arms of the main section of the members.

Among the other aims and objects of this invention may be recited the provision of a 40 device of the character described in which the number of parts are few, the construction simple, the cost of production low and the efficiency high.

Other objects as well as the nature, characteristic features and scope of this invention will be more readily apparent from 45 the following description taken in connection with the accompanying drawings and pointed out in the claims, forming a part of this specification.

The preferred embodiment of the present 50 invention is clearly illustrated in the accompanying drawings, in which:

Figure 1 is a perspective showing the device applied to a portion of a stairway in 55 the course of construction.

Fig. 2 is an enlarged top plan.

Fig. 3 is an end elevation of the invention.

Fig. 4 is an enlarged perspective detail showing the means for adjustably connecting the main sections of the members relative to each other.

Fig. 5 is an enlarged transverse section taken on line 5—5 of Fig. 2 in the direction in which the arrows point.

Similar characters of reference are employed in all of the above described views, to indicate corresponding parts.

Referring now, more particularly, to the accompanying drawings there is provided a stairway including spaced skirting boards 70 1 and spaced stringers 2 arranged parallel to each other and to and between the skirting boards. Steps embodying riser portions 3 and tread portions 4 are mounted on the stringers between the skirting 75 boards in the usual manner. Resting on the stringers between the adjacent riser portions and the skirting boards is an improved stair gage embodying the present invention and indicated in its entirety by 80 the numeral 5.

In the present instance the present invention consists of a pair of sections 6 and 7, which are respectively reduced toward their outer ends to provide diagonal shoulders 8. 85 Blades 9 have their inner ends pivotally connected to the outer terminals of the reduced portions of the sections 6 and 7 through the medium of suitable fastening devices such as bolts 10 while winged nuts 90 11 serve to frictionally clamp the blades 9 at various inclinations relative to the sections 6. The outer ends of the blades are beveled as indicated by the numeral 12 to conform to the inclination of the diagonal 95 shoulders and are adapted to abut the said shoulders when the blades are swung into a closed position. It will be appreciated that the sections 6 and the blades 9 forming the adjustable members constitute a 100 substantially adjustable T-square.

With a view toward providing suitable means for adjusting the sections 6 and 7 relative to each other a tongue 13 extends longitudinally from the inner edge of the 105 section 6 and is provided on one surface with spaced parallel ribs 14 which extend throughout the length of the tongue for a purpose that will presently appear. The inner end of the other section 7 is reduced 110 as indicated by the numeral 15 while the inner surface of the reduced end is provided

with spaced grooves 16 which extend throughout the length thereof and in parallel relation with each other so as to removably receive the spaced ribs 14. The side edges of the reduced end are provided with recesses 17 for a purpose that will presently appear and likewise the main portion adjacent the diagonal shoulder provided by the reduced end is provided with a ledge 18. A substantially rectangular and metallic casing 19 is now provided, the side walls 20 thereof being arranged to engage the opposed recesses 17 while the main portion engages the ledge 18 and the front wall 15 is arranged to abut the inner edge of the reduced end. The casing is removably secured to the reduced end through the medium of suitable fastening devices such as screws 21. The end wall is further provided with an opening 22 which permits of the slidable adjustment of the tongue 13 in the casing. Suitable means such as a set screw 23 threaded in the casing and frictionally engageable with the free face of the tongue, serves to maintain the sections 6 and 7 in a relatively adjusted position. By the arrangement thus described it will be appreciated that the fastening devices 21 coöperate with the side walls 20 and recesses 17 in rigidly yet removably maintaining the casing in position.

In use, assuming that the parts have been assembled in the manner described, the gage is placed upon the tread supporting surface 35 of the stringers as indicated in Fig. 1 and by adjusting the set screw 23 the outer ends of the respective sections 6 and 7 are adjusted to abut the inner surfaces of the skirting boards 1 whereupon the set screw 40 is tightened to maintain the sections in an adjusted position. The blades 9 are now swung upwardly to abut the inner surfaces of the skirting boards and are clamped in a substantially rigid position through the medium of the winged nuts 11. The device 45 is now removed and placed on a board (not shown) to enable the stair builder to determine by the adjustment of the sections and blades the length of the tread and the cut 50 thereof or in other words the inclination of the end edges with respect to the longitudinal edges. It will be also appreciated that when not in use the blades may be folded in alinement with the sections 8 which 55 latter may be adjusted into close relation with each other, thereby placing the entire device in a small compact form that may be readily and conveniently carried.

As many changes could be made in the 60 above construction and many apparently widely different embodiments of this invention could be made without departing from

the scope thereof, and it is intended that all matter contained in the above description or shown in the accompanying drawings shall be interpreted as illustrative and not in a limited sense. It is also to be understood that the language used in the following claims is intended to cover all the generic and specific features of the invention herein described and all statements of the scope of the invention, which, as a matter of language might be said to fall therebetween.

Having thus fully described this invention what is claimed as new and desired to be secured by Letters Patent, is:—

1. A device of the character described including a pair of sections each having one end reduced to provide a diagonal shoulder, 65 a blade pivotally and adjustably mounted on the outer reduced end of each section, the free ends of the blades being beveled for removable engagement with the correspondingly-shaped shoulders, a tongue formed on 70 the opposite end of one of the sections, a casing carried by the opposite end of the other section for slidably receiving the tongue, co-acting means on the tongue and on the adjacent end of the other section for 75 guiding the sliding movement of the sections, and a set screw mounted in the casing and frictionally engageable with the tongue to 80 consequently hold the sections in a relative 85 adjusted position longitudinally of each 90 other.

2. A stair gage including a pair of sections each of which has one end reduced to provide a beveled shoulder, a pair of blades each having one end beveled, bolts 100 for pivotally connecting the blades to the reduced ends of the sections, winged nuts 105 engageable with the blades for clamping the blades at various angles with respect to the sections, the beveled ends of the blades abutting the adjacent shoulders, when not in use, a tongue projecting from the opposite end of one of the sections, spaced longitudinal ribs on one surface of the tongue, the opposite end of the other section being reduced and provided with spaced longitudinal grooves, a casing carried by the last 110 mentioned reduced end of the other section and provided with an opening for slidably receiving the tongue and permitting of the 115 ribs to slidably engage the grooves so that the sections may be adjusted longitudinally with respect to each other, and a set screw mounted in the casing for frictional engagement with the tongue to consequently hold 120 the section in an adjusted position.

In testimony whereof I affix my signature.

JOSEPH D. MURVINE.
